(57) **CLAIM**

I claim the ornamental design for a display device with a probing dental keyboard graphical user interface, as shown and described.

DESCRIPTION

A portion of the disclosure of this patent document contains material to which a claim for copyright and trademark is made. The copyright and trademark owner has no objection to the reproduction of the patent document or the patent disclosure, as it appears in the U.S. Patent Office records, but reserves all other copyright and trademark rights whatsoever.

FIG. 1 is a front view of a display device with a probing dental keyboard graphical user interface; and,
FIG. 2 is a second embodiment thereof.

The dash-dot broken lines showing a display device, and the even broken lines showing elements of the graphical user interface illustrate portions of the article and form no part of the claimed design.
